Specification for Design.

Patented May 13, 1919.

Application filed January 29, 1919. Serial No. 273,922. Term of patent 7 years.

To all whom it may concern:

Be it known that I, Dr. WALTER RYSER, a citizen of the Swiss Confederation, residing at Milwaukee, in the county of Milwaukee and State of Wisconsin, have invented a new, original, and ornamental Design for Containers, of which the following is a specification, reference being had to the accompanying drawing, forming part thereof.

The figure is a perspective view of a container, showing my new design.

I claim:

The ornamental design for a container, as shown.

In testimony that I claim the foregoing I have hereunto set my hand at Milwaukee, in the county of Milwaukee and State of Wisconsin.

DR. WALTER RYSER.
